KNOB SPINDLE LOCK

Morris Falk, Leominster, Mass., assignor to Independent Lock Company, Fitchburg, Mass., a corporation of Massachusetts

Application September 9, 1938, Serial No. 229,050

8 Claims. (Cl. 292—359)

This invention relates generally to spindle locks, and more particularly to a latch type of spindle lock having associated therewith means for locking the latch so that the door cannot be opened.

More specifically it relates to a spindle lock of the "non-mortise" type, that is one that may be installed by drilling or otherwise cutting small passages in the door to which it is applied, as distinguished from the "mortise" type of lock, the installation of which necessitates the cutting of a large rectangular opening in the door.

My invention has been disclosed herein, in its application to what is commonly known as a bathroom lock, in which a locking arrangement is provided on one side of the door, namely the inside or bathroom side of the door, so that the occupant of the bathroom can lock or unlock the door, while such locking or unlocking cannot be effected from the outside, except where an emergency arrangement is provided, such as will be described in connection with my invention. However it will be understood that it is not necessarily restricted to this type of lock.

Among the general objects of my invention is the provision of a knob spindle lock of the non-mortise type that is simple, compact, reliable in operation, easily installable and low in cost.

Among the more particular objects of my invention are the provision of a knob spindle lock having latch operating means and locking means both operable by one hand, the provision in a lock having latch operating means and locking means, of means interconnecting them so that the locking means may be used to operate the latch operating means, the provision in a lock having latch operating means and locking means, of means interconnecting them so that the latch operating means may be used to operate the locking means, the provision in a lock of a locking arrangement that may be accommodated inside of one of the rose plates of the latching mechanism, and the provision in a lock of an extremely simple and effective locking mechanism having characteristics resembling to some extent an intermittent drive or Geneva stop motion, whereby locking action as well as latch setting position for locking may be combined in a device of the character herein contemplated. Thus my invention has for its object the provision of a simple and inexpensive assembly which may be combined with existing latches and associated with the spindle thereof to provide a locking and latch setting device.

To attain these objects and such further ob-

jects as may appear herein or be hereinafter pointed out, I make reference to the accompanying drawing, forming a part hereof, in which

Figure 1 is a fragmentary end view of a door having my improved door lock applied thereto; 5

Figure 2 is a front elevational view of the parts shown in Figure 1, with the door knob removed;

Figure 3 is a sectional view of my improved latch lock taken substantially on the line 3—3 of Figures 1 and 6, looking in the direction of the 10 arrows, and showing the parts in a position in which the latch spindle is locked against turning movement;

Figure 4 is a view similar to Figure 3, but showing the latch spindle unlocked and turning clockwise into one of its limiting positions; 15

Figure 5 is a view similar to Figure 3, but showing the latch spindle unlocked and turned counter-clockwise into its other limiting position;

Figure 6 is a sectional view substantially on the line 6—6 of Figure 3 looking in the direction of the 20 arrows, but on an enlarged scale.

Referring to the drawing in detail the numeral 18 therein designates a portion of a door provided with a bore 12 through which runs the square 25 spindle 14 of a latch mechanism of conventional type. A pair of door knobs 16 and 18 are shown at either end of the spindle, being held thereon by screws 19 in the customary manner. A pair of 30 rose or escutcheon plates 20 and 22, held in place on the door by screws 28 are also provided, and the latch spindle 14 passes through openings 24 therein. At 26 is shown a seat for the hub portion of each door knob, and the two seats provide the bearings in which the door knob and spindle 35 combination turns. Manipulation of the door knobs and the consequent movement of the latch spindle will serve to operate the latch bolt 30, which is shown as slidable in a shell or lining 31 positioned in a bore extending inward from the 40 edge of the door toward the bore 12. The operating mechanism for the bolt is not shown; it will be understood that it is of conventional type.

So far I have described only the parts of a latching mechanism of a type in common use. I 45 will now proceed to describe the features that characterize the illustrative embodiment of my invention.

There is shown a plate 32 on which is mounted the parts of my improved locking arrangement, 50 and this plate is shown as positioned underneath and inside the rose plate 20 and as held in place on the door by screws 34 or any other preferred means.

Pivots mounted on the plate 32 is a disc 36. 55

The details of its pivotal mounting may include a bushed extension 37 on the disc, journalled in a suitable opening in the plate 32 and surrounded by a washer 38 to reduce friction. The disc 36 is provided with a square opening 39 through which the latch spindle 14 passes in close engagement and whereby the disc is constrained to move with the latch spindle.

The disc 36 may be described as of generally circular contour with portions cut away therefrom to give it the peculiar configuration shown in the drawing.

Means are shown for limiting the turning of the disc 36. Such means comprise a recessed portion 40 terminating in shoulders or abutments 42 and 43 adapted to engage a stop lug 44 struck up or carried by the plate 32, and serving thereby to limit the turning of the disc 36 as well as of the latch spindle and of the door knobs 16 and 18.

Figure 4 shows the limiting position of the disc 36 when it is turned clockwise, and Figure 5 shows its limiting position when it is turned counter-clockwise.

The disc 36 is further shown as provided with a concavely contoured recess 46, the contour of which is formed on the same radius and the same center as the peripheral portions of a locking plate 48 that serves to lock the disc 36 against rotation when desired, as will now be explained.

The locking plate 48 is also pivotally mounted on the base plate 32 and the details of its mounting may comprise a bushed extension 50 on the plate 48 journalled within an opening in the plate 32 and surrounded by a washer 52 to reduce friction. The locking plate 48 has a square opening therein through which is shown passing the square locking spindle 54, in close engagement, so that the locking plate 48 is constrained to move with the spindle. The latter is shown as carrying at one end, namely the inner or bathroom end thereof, an operating handle 56 having a hub portion journalled in the rose plate 20, and whereby the locking spindle may be turned. The hub portion of the handle 56 has a shoulder abutting plate 20 so as to limit endwise movement of the spindle 54 in one direction, while a pin 58 limits endwise movement of the locking spindle 54 in the opposite direction. A washer 60 is shown interposed between the pin 58 and the rose plate 20 to insure free turning movement of the spindle 54.

The locking plate 48 is also of generally circular contour with cut-away portions just like the disc 36. Means are provided for limiting its rotation; such means may comprise a cut-away portion 62 provided with shoulders 64 and 65 adapted to engage a stop lug 66 carried by the base plate 32.

The locking plate 48 is further provided with a concavely contoured recess 68 formed on the same radius and on the same center as the peripheral portions of the disc 36.

The configurations and mountings of the disc 36 and the locking plate 48 just described, and which in certain respects resemble a Geneva stop motion, permit of an interaction between them that may be understood by referring particularly to Figures 3, 4 and 5.

In Figure 3 the locking plate 48 is in one of its limiting positions, namely its locking position, and it will be observed that in this position its circular peripheral portion extends into the concave recess 46 of the disc 36 and completely fills it, with the result that while the locking plate 48

is free to turn, the disc 36 is locked against rotation. It will further be observed that when the locking plate 48 is in its locking position the disc 36 and consequently the latch spindle are in such a position that the latch bolt 30 is in its 5 protruded position.

In Figure 4 the locking plate 48 is shown in a position in which the circular peripheral portion of the disc 36 has entered the concave recess 68 of the locking plate 48, and the latter is locked 10 against rotation, while the disc 36 is free to turn, as far as the effect of locking plate 48 on it is concerned. In the particular position shown in Figure 4 the disc has been turned clockwise into its limiting position with the shoulder 42 against 15 the stop lug 44; consequently it can only be turned counter-clockwise from its position shown in Figure 4, and its turning in the counter-clockwise direction is again limited by the stop lug 44, as shown in Figure 5, which shows 20 the other limiting position of the disc 36.

In Figure 5, while the locking plate 48 is shown in the same position as in Figure 4, it is not locked against rotation, since it will be obvious that it can be turned in a counter-clockwise direction, and when so moved it will exert a driving action on the disc 36 that will result in the disc 36 and plate 48 assuming the positions of Figure 3 in which the disc 36 is locked. Ordinarily, of course the mechanism associated with 30 the latch bolt will cause the spindle 14 and disc 36 to move automatically into the position of Figure 3, but this driving action may be utilized where for some reason the disc 36 is caught or held in the position of Figure 5. 35

Conversely, as the locking plate 48 is moved counter-clockwise from its position of Figure 5, it will be obvious that until a critical position is reached as in Figure 3, the plate 36 may be turned thereby clockwise thus using the locking plate 48 to turn back the plate 36 into the latching position of Figure 3. This characteristic of my lock may prove valuable where in manipulating the door knobs to turn the latch spindle the latch is jammed so that the spring 45 therefor is ineffective to return it to the latching position such as in Figure 3. The driving action which may be transmitted from the plate 48 to the plate 36 has additional utility in setting the spindle shaft for the latch in the appropriate 50 position for locking.

In order to increase the range within which this relative driving action can take place I have shown the contours of the recess 46 gradually merging into the circular peripheral contour of disc 36. This is effected by rounding off the corners that would normally be formed at the meeting points of the recess and the periphery; this rounding off is indicated at 47. A similar rounding off is indicated at 69 for the locking plate 48. 60

As clearly appears from Figures 3, 4 and 5, the locking plate 48 has two limiting positions determined by the lug 66, one of which, in which the disc 36 (and latch spindle 14) are locked, is shown in Figure 3, and the other of which, in which the disc 36 (and latch spindle 14) are free is shown in Figures 4 and 5. To pass from one position to the other requires a quarter of a turn of the locking spindle 54.

In order to hold the locking plate 48 yieldably in either one of these positions I have shown means such as a leaf spring 70 having one end 72 doubled back and pivotally mounted as at 74 on the base plate 32. The end 72 bears against a lug 76 struck up or carried by the plate 32 75

and determines the position and the tension of the spring 70, the curved free end of which bears against the edge of the locking plate 48 and assumes stable positions when it enters the recesses 64 and 68 in which it resists displacement of the locking plate 48. At 80 is shown a tongue adapted to prevent outward movement of the spring 70.

It will also be observed that the disc 36 is limited in motion to one quarter of a turn. By so limiting the disc 36, accurate assembly is greatly facilitated. After the latch spindle 14 has been inserted in the bore 12 and the locking arrangement is placed thereon by passing the spindle 14 through the square opening in the disc 36, all possibility of an incorrect relative positioning of the disc 36 relatively to the locking plate 48 is precluded, and because the disc 36 is limited to a turning of one-eighth of a turn to either side of its locking position, the relative positions of the spindle 14 and disc 36 are determined and limited to a correct interfitting thereof.

The spindle 54 is shown as positioned within the bore 55 of the door and as extending almost through the door to the outside thereof. It is shown as provided with a recess 82 at its outer end into which is adapted to fit a special key 84, indicated in dotted lines in Figure 6, and intended for emergency use. In order to permit insertion of the key 84, an opening 86 is provided in the outer rose plate 22.

The operation of the device will now be briefly summarized. When it is desired to lock the door, the door knob is positioned, due to the natural spring action of the latch or by reason of the fact that it is first manipulated, so as to assume the position of Figure 3, and the handle 56 is then turned counter-clockwise which will cause the parts to assume the position of Figure 3, holding the latch locked. Manifestly locking cannot be effected in the position of Figure 4, since the locking spindle 54 is held against rotation. If the door knob is released it will be caused, by the conventional spring mechanism associated with the latching bolt, to assume the position of Figure 3, and the locking plate 48 can then be turned into the locking position if desired.

Should manipulation of the spindle 54 be effected while the plate 36 is in a position shown in Figure 5 the plate 36 will be moved to the position shown in Figure 3. Should also the plate 36 be in the position shown in Figure 5 by reason of jamming or sticking of the latch 30, a driving action will be transmitted from the plate 48 to the plate 36. It will thus be observed that accurate alignment of the plate 48 and plate 36 by manipulation of the spindle 14 need not be obtained in order to effect locking of the spindle and that relatively extended areas of contact effect the locking action, minimizing wear and providing a durable construction from relatively thin plate like members.

Conversely as the locking plate 48 is moved counterclockwise from the position shown in Figures 4 and 5 to the point where the peripheral surface of the extension 77 is brought in contact with the camming edge 78 of the spring 70 at a more or less critical position, the plate 36 upon rotation in a counter-clockwise direction may serve to trip the plate 48 to the unlocking position. Thus if an irresponsible person should turn the locking plate 48 from its position shown in Figure 5 in a counter-clockwise direction to the point where the peripheral surface or edge of the extension 77 of the plate 48 is in contact with

the spring-end 78, then in that event the latching spindle 14 may be operated by the external knob 18 to return the latching plate 48 to its position shown in Figures 4 and 5, whereupon the spindle is then free to be rotated for unlatching the latch 30. In this manner it will be observed that the device has the property of transmitting movement from the plate 48 to the plate 36 and conversely from the plate 36 to the plate 48 (when a critical position of the plate 48 is obtained) not only for emergency purposes but when improperly operated by some irresponsible individual.

It will also be observed that by aligning of the spindles 14 and 54 to each other by rotatively connected mounting, a compact assembly as provided to some degree carries out certain phases of my invention disclosed and claimed in my application Serial No. 176,409, filed November 26, 1937, in that an existing simple door latch may be modified to provide it with locking mechanism and by the simple expedient of a boring 55 through the thickness of the door provide emergency means for operating the door locking device.

In general it will be observed that I have provided a simple and inexpensive locking mechanism where accuracy of alignment of the latch is not necessary for operation for its intended purpose. It will also be observed that while the preferred form of my invention contemplates the utilization of all of the features illustrated, parts thereof may be utilized and the scope of my invention is to be judged by the scope of the appended claims.

Having thus described my invention and illustrated its use, what I claim as new and desire to secure by Letters Patent, is—

1. In a door lock comprising a latch operating spindle adapted to pass through a bore in a door, a rose plate adapted for fastening to one side of the door and through which one end of the spindle is adapted to protrude, and locking mechanism for said latch operating spindle adapted to be positioned beneath said rose plate and comprising a rotatable member coaxial with said spindle and rotatable therewith, and a rotatable element adapted to lock said member against rotation and means for rotating said element adapted to extend into a second bore in said door and carrying operating means at one end, and adapted to be engaged by a key at its other end and arranged to be extended within the confines of said second bore in said door.

2. In a door lock of the non-mortise type, a latch spindle and a lock spindle, said spindles being mounted for pivotal movement in spaced relation to each other, a disc carried on said latch spindle, said disc being of generally circular conformation, with portions cut away from its periphery, a locking plate carried on said lock spindle, and said locking plate being also of generally circular conformation, with portions cut away from its periphery, said disc having a concavely contoured recess therein adapted to be filled by the circular peripheral portions of said locking plate, and said locking plate having a concavely contoured recess therein adapted to be filled by the circular peripheral portions of said disc, whereby said locking plate may lock said disc against rotation, and said disc may lock said locking plate against rotation, and whereby when the wall portions of the concavely contoured recesses of the disc and the locking plate are interengaged the disc may drive the locking plate and the locking plate may drive the disc.

3. A locking device for a door latch operated by a spindle comprising a plate adapted to be mounted beneath a rose plate associated with said spindle, a disc having means rotatively mounting the same on said plate and including means engaging said spindle for mounting the same for positive movement with said spindle, a locking disc having means rotatively mounting the same on said plate, the peripheral edges of said discs having interengaging connection of extended area for transmitting movement to each other and for locking engagement of the one in respect of the other.

4. Locking mechanism for a door lock having a square latch operating spindle, comprising a base plate having an aperture therein through which the latch spindle passes, a disc having a bushed extension mounted on said base plate having a bearing in said plate and having a square opening therein adapted to receive said latch operating spindle therein whereby it will turn with said spindle, said disc being of generally circular conformation, having a concavely contoured recess cut out from the peripheral portions thereof, and having a second recess also cut out of the peripheral portions thereof of a shape to form shoulders, a lug on said base plate and adapted to engage said shoulders and thereby to limit the rotation of said disc, a disc-shaped locking plate 30 rotatably mounted on said base plate, said disc being also of generally circular conformation and having a concavely contoured recess cut out from the peripheral portions thereof and a second recess shaped to form shoulders cut out from the peripheral portions thereof, a second lug struck up out of said base plate and adapted to engage said shoulders on the locking plate so as to limit its rotation, and a circular portion of said disc being adapted to fit into said concave recess of 40 said locking plate so as to hold said locking plate against rotation, and a circular portion of said locking plate being adapted to fit into said concave recess in said disc so as to hold said disc against rotation, spring means mounted on said base plate and engaging the periphery of said locking plate, whereby it will yieldably hold said locking plate in one of two positions determined by said recesses in said locking plate and corresponding respectively to a position in which said circular portion of the disc periphery fits into the concave recess of the locking plate and a position in which said circular portion of the locking plate fits into the concave recess in said disc, and means for setting said locking plate into either 55 one of said positions.

5. Locking means for a door lock having a latch bolt and a latch operating spindle for the latch bolt, said lock including an assembly whereby rotation of said spindle from the normal position in a clockwise and counter-clockwise direction will retract the latch bolt, the combination comprising a plate assembly positionable to one side of said lock and through which said latch operating spindle may extend, said plate including a lock operating spindle, complementary locking means comprising a substantially circular member and a locking element operatively carried respectively by said spindles for effecting locking of said latch operating spindle by rotary movement of said lock operating spindle, said member including an orifice therethrough and through which said latch operating spindle may extend in keying engagement, and being formed and mounted on said plate to permit rotation in a clockwise and counter-clockwise direction for distances in either direction of rotation, 70

permitting retraction of the latch bolt, said member also including a peripheral recess adapted to be interfitted by an unrecessed edge portion of said locking element operated by rotation of said lock operating spindle, said locking element including a recess so that the unrecessed portion of the member may pass by the recessed portion of said element and permit clockwise and counter-clockwise rotation of said latch operating spindle for retraction of said bolt and whereby, by alignment of said element with its unrecessed portion interfitting with the recessed portion of said member, said latch operating spindle will be held in locked position and whereby positioning of the recessed portion of 15 said element interfitting with the unrecessed periphery of said member, the latch operating spindle may be rotated in a clockwise or counter-clockwise position for the purposes aforesaid.

6. Locking means for a door lock having a latch operating spindle, said lock including an assembly whereby rotation of said spindle in a clockwise and counter-clockwise direction from a normal position will retract the latch, the combination comprising a base plate through which the latch operating spindle extends, a member rotatably mounted on said base plate and provided with an opening adapted to slidably receive said latch operating spindle in keyed engagement with said spindle, said member having a pair of shouldered portions defining a peripheral recess, the distance between the mid-point of said recess and a shouldered portion being sufficient to permit rotation of the latch operating spindle to retract the latch upon rotation of said latch operating spindle in either of the directions aforesaid, and locking means mounted for rotation on said base plate and adapted, in certain positions thereof, to engage and to lock said member against rotation, and means to limit the rotation 40 of said member lying in the path of said shoulders of said member, said means comprising a lug on the base plate normally located adjacent the mid-point between said shoulders of said member.

7. Locking mechanism for a door lock having a latch operating spindle, said lock including an assembly whereby rotation of said spindle clockwise and counter-clockwise may retract the latch of said lock, the combination therefor comprising a base plate through which the spindle extends, a member rotatably mounted on said base plate and provided with an opening adapted to slidably receive said latch operating spindle in keyed engagement with said member, said member being mounted for free rotation in a clockwise and counter-clockwise direction and having a pair of shouldered portions defining a peripheral recess, the distance between the mid-point of said recess and a shouldered portion being sufficient to retract the latch upon rotation of said latch operating spindle in either of the directions aforesaid, and locking means mounted for rotation on said base plate and adapted, in certain positions thereof, to engage and to lock said member against rotation, and means to limit the rotation of said member comprising an element lying in the path of the shoulders of said member, said means comprising a lug on the base plate and normally located adjacent the mid-point between said shoulders of said member, said locking means comprising a generally disc-shaped element and including cammed peripheral portions, a spring mounted upon said base plate adapted to engage said cammed portions of said element, resiliently to 75

urge the same into locking or releasing positions. 8. Locking means for a door lock provided with a latch operating spindle, said lock including an assembly whereby rotation of said spindle in either a clockwise or counter-clockwise direction from a normal position will serve to retract the latch of said lock, the combination comprising a base plate adapted to be fit beneath the rose plate of said door lock and 10 through which the latch operating spindle extends, a member rotatably mounted on said base plate and provided with a central opening adapted to slidably receive said latch operating spindle in keyed engagement with said member, 15 said member having a pair of shoulder portions defining a recess, the distance between the mid-point of said recess and a shoulder portion to

either side thereof being sufficient to permit rotation of the latch operating spindle in a direction and for the purpose aforesaid, and a locking element for said spindle rotatably mounted on said plate having a pair of shoulder portions and adapted, in certain positions thereof, to engage and to lock said member against rotation and means to limit the rotation of said member and of said locking element to a predetermined partial rotary position, said means lying in the 10 path of the shoulder portions of said member and locking element, said means comprising lugs on the base plate and lying in the path of said shouldered portions of said member and locking element. 15

MORRIS FALK.
